BURGLAR TRAP

Paul A. Fiebiger, New York, N. Y.

Application September 11, 1935, Serial No. 40,174

4 Claims. (Cl. 20—1.01)

This invention refers to burglar traps and is intended to prevent the escape of burglars with their loot after an attempted hold-up of an establishment.

With this end in view, the invention consists in providing the establishment or store to be protected with an auxiliary door or gate operable by switches distributed at strategic points throughout the establishment.

One of the objects of the invention is to provide a gate which closes quickly and locks itself in such closed position upon closing of one of the switches.

Another object is to provide the gate and its locking mechanism in a jamb forming with it a practically self-contained unit, readily applicable in combination with existing doors.

A further object is to provide a complete gate unit of this kind which can be economically manufactured and by virtue of its construction lends itself readily for production in quantities.

Other objects will become apparent after a perusal of the following specification and its accompanying drawings, in which

Fig. 1 is an elevational view of a door jamb with a single gate embodying the principles of the invention, the gate being shown in an open position;

Fig. 2 is a similar view with the gate in a closed and locked position;

Fig. 3 is a longitudinal fragmentary sectional view of the jamb and its locking mechanism and part of the gate drawn at a larger scale and in a closed position;

Fig. 4 is a similar fragmentary sectional view showing the locking mechanism in an unlocked position just prior to reopening the gate;

Fig. 5 is a fragmentary detail elevational view of the gate supporting means in the top of the jamb;

Fig. 6 is a cross-sectional view along the plane of line 6—6 in Fig. 5;

Fig. 7 is a cross-sectional view along the plane of line 7—7 in Fig. 3;

Fig. 8 is an elevational view of a modified construction of a door jamb with a double gate in a closed position;

Fig. 9 is an enlarged fragmentary view, partly in section, of the locking mechanism of the double gate where its separated lower portions meet;

Fig. 10 is a fragmentary cross-sectional view along the plane of line 10—10 in Fig. 4;

Fig. 11 is a fragmentary cross-sectional view along the plane of line 11—11 in Fig. 3; and

Fig. 12 is a fragmentary cross-sectional view along the plane of line 12—12 in Fig. 9.

Like characters of reference denote similar parts throughout the several views and the following specifications.

In Figs. 1 to 4 are shown elevational and fragmentary sectional views of a gate of the single folding type. In these figures is clearly shown a jamb 20 of the usual U channel construction. Its top cross piece has two inwardly and again upwardly bent flanges 20a for the guidance of two rollers 21 connected by a shaft 22 and from which is suspended a bracket strip 23 for the folding gate 24 consisting of the usual pairs of uprights 25, end pieces 26 and 26a, and cross pieces 27 pivotally disposed between the uprights 25. The tops of the pairs of uprights project into the top cross piece of the jamb and their bottoms into a groove 28 of a saddle 29.

The end piece 26a is secured to the upright portion 20b of the jamb. The other end piece 26 has at its top an L-shaped extension 30 to which is fastened a latch bar 31 having a latch hook 32 at its end. In the closed position the hook 32 engages a projecting bolt 33 of a solenoid 34 mounted upon the jamb. 35 and 36 are wires of an electric circuit connecting the solenoid to a suitable switch. The bottom of end piece 26 has a laterally projecting ratchet bar 37 having a plurality of teeth 38 and a relatively pointed end 39. The ratchet bar is adapted to slide within the groove 28 of the saddle 29.

40 is a weight of substantially square cross-section guided within the other upright 20c of the jamb 20. 41 are ratchet teeth at one side of the weight 40. The weight is suspended by a cable 42 travelling over a roller 43 in the top of the jamb and then connected laterally with the L-shaped extension 30 at the top of end piece 26. In the open position of the gate shown in Fig. 1 and in dotted lines in Fig. 3 the weight is at the top of the upright member 20c of the jamb while the latch hook 32 engages the bolt 33 of the solenoid, as clearly indicated in Fig. 1.

44 is a vertically disposed latch bar pivotally supported at 45 within a housing 46 at one side of the upright member 20c. Its lower portion is inwardly bent at 47 and projects within the member 20c through an opening 48. The lower end of the bar 44 is held toward the outer wall of the member 20c by means of a tension spring 49. The upper end of the latch bar 44 terminates in a hook 50 the end of which normally projects into the member 20c through an opening 51. The outward travel of the bar 44 is limited by a strap 52

in such a way that the bar can pivot to permit its tilting to an extent sufficient for the hook 50 to be entirely within the housing 46.

At the bottom of the upright 20c is a bolt 53 slidably held thereto by brackets 54. Its bottom end projects into the groove 28 of saddle 29 and there is adapted to engage the ratchet teeth 38 of the bar 37. Its top end 55 is bent over at right angles at 56.

10 Near the bottom of the latch bar 44 and the top 55 of the bolt 53 is a lock 57 consisting of the usual cylinder 58 operable by a so-called "Yale" key in the usual manner. A center portion of the lock is flattened at 59 for the purpose specified hereafter.

15 The operation of the device is as follows:

If an establishment has been held up and it is desired to prevent the escape of a burglar with his loot, it is only necessary to close any of the 20 switches which may be placed at convenient points, as for instance, behind a counter, operable by one's foot, if so preferred. This closes the electric circuit and magnetizes the solenoid 34 which is of a conventional type and which upon 25 magnetization draws up the bolt 33. This disengages the latch hook 32. The weight 40 is then permitted to fall downwardly within the member 20c of the jamb and by reason of its weight draws along the folded gate until its end piece 26 comes 30 to a stop at member 20c, thus closing the door or gate opening. This position is clearly shown in Fig. 3. The vertical latch bar in this position engages the ratchet teeth 41 and the bottom bolt 33 has dropped by gravity into the teeth 38 of 35 the horizontal bar 37 of the gate. In this position therefore the gate is securely locked at the side by virtue of the ratchet teeth in the weight 40 which prevent the weight from being forced upwardly, and at its bottom by the bolt 33 also 40 engaging the ratchet teeth 38 which prevent a return movement of the gate.

An audible signal may be employed in connection with the gate which may be sounded upon closing of the circuit.

45 The gate cannot be opened until and unless the lock is turned. To do so, it is necessary to insert the key and turn the cylinder and its flattened portion 59, which is so disposed in relation to latch bar 44 and bolt 53 that when turned it engages the lower end of the bar 44 turning it about its pivot 45 whereby the hook 50 becomes disengaged from the teeth 41 of the weight 40. Simultaneously the flattened portion 59 engages the top end 55 of the bolt 53 and lifts its bottom out 55 of the teeth 38. This position is clearly illustrated in Fig. 4. The gate can then be opened by hand and returned to the open position to be held there by bolt 33 of the solenoid after the opening of the switch.

60 The pointed and tapered end of the bottom ratchet bar 37 serves not only the purpose of engaging easily the bolt 53, but also tends to keep the groove 28 of the saddle 29 clean and in workable condition.

65 In Fig. 8 is shown a double folding gate in a closed position. All parts which are identical in operation and construction to corresponding parts of the single gate have been given the same ref-

erence numbers and need not further be explained here. The principal difference is in the disposition of the locks. Three individual locks must be used, one each for the vertical latch bars 44 and one for the bottom bolt 53. The end pieces 5 26 of the double gate come to a stop at a cross bar 60 in the groove 28 of the saddle 29. In all other respects the operation of the double gate is the same as the single.

It is understood that various changes of form, 10 proportions and minor details of construction may be resorted to without departing from the principles or sacrificing any of the advantages of the invention as defined in the appended claims.

15

What I claim as new, is:

1. A burglar trap including a gate, a bolt to keep the gate in an open position, a counter-weight connected to the top of the gate tending to close the same, electric means to withdraw the said bolt to permit the gate to close, 20 a latch bar for engaging the said weight and a latch bolt for engaging the lower end of the gate when the gate is in a closed position, the said bar and latch bolt being adapted to prevent its opening, and a lock having means to disengage the said latch bar from the said weight and the said latch bolt from the gate to permit its reopening.

2. A burglar trap comprising a unitary structure including a jamb, a folding gate within 30 the jamb, means to keep the gate in an open position, a counter-weight adapted to close the gate, electric means to release the gate from an open position and permit its closing, a latch bar at the side of the jamb adapted to engage 35 one end of the gate when closed, a latch bolt at the bottom of the jamb adapted to engage the lower end of the gate when closed, and a lock having means to disengage the said latch bar and latch bolt from the said gate to permit 40 its reopening.

3. In a device of the kind described, a jamb, a folding gate within the jamb, a counter-weight having ratchet teeth connected to the gate and adapted to close the same, and a latch bar at 45 the side of the jamb and adapted to engage the teeth in the said weight for locking purposes, when the gate is closed.

4. A burglar trap comprising a unitary structure including a jamb formed of hollow uprights 50 and a top cross-member and a bottom saddle, a folding gate within the jamb, means in the top cross-member to keep the gate in an open position, a counter-weight within one of the said uprights adapted to close the gate and having 55 ratchet teeth, electric means to release the gate from an open position and permit its closing, a latch bar within the same upright adapted to engage the teeth of said weight when the gate is closed, a latch bolt within the same upright 60 and near its bottom adapted to engage the lower part of the gate when closed for locking purposes, and means to disengage the said latch bar from the said weight and the said bolt from the gate 65 to permit its reopening.

PAUL A. FIEBIGER.
